UNITED STATES PATENT OFFICE.

ALLISON A. CLOKEY, OF RUTHERFORD, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed June 18, 1920. Serial No. 389,842.

To all whom it may concern:

Be it known that I, ALLISON A. CLOKEY, a citizen of the United States, residing at Rutherford, in the county of Bergen, State of New Jersey, have invented certain new and useful Improvements in Signaling Systems, of which the following is a full, clear, concise, and exact description.

This invention relates to signaling systems and apparatus and more particularly to a new form of relay adapted for use as a transmitting relay for submarine cable signaling and the like.

The principal object of the invention is to provide means for rapidly and efficiently transmitting signals to a line and more specifically to provide an improved relay arrangement possessing operating features of the well known mechanical types of relay now used together with certain additional characteristic advantages.

In certain types of telegraph systems, especially submarine cable systems, it is necessary to employ a pole changing relay intermediate the transmitting apparatus and the line or cable. In some of the systems this pole changing relay is designed to effect the closure of a contact and maintain such contact closed for a considerable length of time. Such being true it is necessary in order to open this contact to transmit an impulse of a polarity opposite to the impulse which previously operated the relay for closing such contact. The chattering occurring upon the closure of the contacts of all types of relays heretofore employed is objectionable for reasons well known to those versed in the art. The effect of this chattering combined with the mechanical limitations of the relay is to reduce materially the speed at which signals may be transmitted. For ordinary slow speed signaling this feature is not seriously objectionable because the time occupied by chattering of the contacts represents but a small percentage of the total signal interval. However as the speed of signaling is increased, it becomes a very important factor and is detrimental to the rapid transmission of well formed signals. The present invention is designed to obviate the difficulties experienced due to the operation of metallic contacts.

In attaining the above object the inven-

tion provides a transmitting relay arrangement for use in connection with telegraph systems, which impose no limitations on the speed at which telegraph signals may be transmitted, so far as the transmitting relay is concerned. This is accomplished by making use of a three-electrode electric discharge device, such as the well-known audion or thermionic relay, operating by pure electron discharge, or similar three-element tube operating with ionized gas, the potential of the grid electrode being regulated by an electrostatic means connected in the input circuit of the discharge device. In the preferred form of the invention this electrostatic means is a condenser and is designed to be charged in accordance with the actuation of suitable transmitting apparatus which connects thereto a source of signaling current. When the condenser possesses a charge a potential will be applied to the grid electrode of the electric discharge device which is of sufficient value to permit current to flow in the plate circuit, thereby applying a definite transmitting potential to the line or cable. Since the input circuit of the discharge device is of an extremely high resistance, the condenser will discharge very slowly, thereby maintaining a flow of current in the line as long as the condenser retains a charge.

A better understanding of the invention may be had from the following detailed description, when considered in conjunction with the accompanying drawing, wherein Fig. 1 shows a simplified arrangement employing a condenser in the input circuit of an electric discharge device as a relay for effectively transmitting telegraph signals; Fig. 2 shows an alternative arrangement for transmitting positive and negative impulses, such as are commonly used in cable telegraphy; while Fig. 3 shows a more symmetrical circuit arrangement using two electric discharge devices in conjunction with a distributor and a tape transmitter for transmitting signals of positive and negative polarity over a cable connected thereto.

Referring now to the drawing, and especially to Fig. 1, there is shown a line 5-5 extending from a distant station (not shown) and terminating, as shown in this figure, in the output circuit of an electric discharge device or vacuum tube 7, said

output circuit comprising a resistance 6, the heated filament 8, the anode or plate electrode 9, and a resistance 10. The input circuit of said tube comprises the grid electrode 11, the heated filament 8, the condenser 12, and the battery 13. Associated with the condenser 12 is a set of transmitting keys 14 and 15, which control the application of a source of battery with the terminals of the condenser. There is also provided in conjunction with the condenser 12, a third key 16, which serves to short-circuit the condenser 12, thereby discharging the same and reducing the line current to zero. The battery 13 is placed in the grid circuit to hold the grid electrode 11 negative with respect to the filament. Thus when no charge is retained by the condenser 12, a current will flow through the resistance 10 and a difference of potential will exist between the terminals of this resistance. However, in order to prevent current from normally flowing in the line 5-5, a battery 17 is placed in the output circuit. This battery is adjusted so as to be equal and opposite in polarity to the difference of potential existing between the terminals of the resistance 10. This thereby reduces the normal current in the circuit 5, 5 to zero.

In the transmission of signals, keys 14 and 15 are operated depending upon the character of the signal desired to be transmitted. If key 14 is depressed for a short time only, the condenser 12 becomes positively charged, thereby making the grid electrode 11 more positive with respect to the heated filament 8 for effecting the transmission of a signal representing a dot. This causes an increase in the current flowing through the resistance 10 and a consequent increase in the difference of potential between the terminals of such resistance. When such a condition exists, this difference of potential is greater than the potential of the battery 17. Current is thereby caused to flow in the output circuit in a direction opposite to the battery 17, and in turn over the line 5. Since the resistance of the input circuit of the tube 7, with all of the keys open, is of a very high value, the condenser 12 will discharge very slowly, and during the time a charge is retained thereby, current in the output circuit continues to flow. Thus it is seen that the provision of a condenser in the input circuit of an electric discharge device arranged to transmit telegraph signals, accomplishes the same result as the mechanical type of locking relay; that is, a flow of current is maintained to the line for a considerable length of time after the transmitting key has been released. The provision of such an arrangement, however, at the same time permits the speed of signaling to be greatly increased as explained above.

When it is desired to transmit a space signal, key 16 is depressed. As previously brought out the depression of this key short-circuits the condenser 12, thereby causing the same to become completely discharged. Upon the discharge of the condenser 12, the current in the circuit 5, 5 is at once reduced to zero. This in effect produces the same result as if the line were grounded through a resistance following each signal impulse.

If it is desired to transmit a signal representing a dash, key 15 would be depressed. The depression of this key 15 connects the negative terminal of the battery with the condenser 12, which thereupon becomes negatively charged. The condenser 12, being charged negatively, makes the grid electrode 11 more negative with respect to the heated filament 8, and thereby causes a decrease in the current flowing through the resistance 10, this in turn causes a drop in the difference of potential normally existing between the terminals of this resistance. The potential of the battery 17 is now greater than the difference of potential existing between the terminals of the resistance 10, and in consequence thereof a current flows in the line 5 in the direction of the battery 17.

In the arrangement shown in Fig. 2, the line or cable 18 is normally grounded through a resistance 19. This thereby makes it possible to transmit signals composed of positive and negative impulses, as is the common practice in short cable and land line signaling. The output circuit of the vacuum tube 7, as described in connection with Fig. 1, is connected with the cable 18, but in this case through a sending condenser 20, the purpose of which is well known to those skilled in the art. The input circuit thereof is arranged in substantially the same manner as that in Fig. 1, except that a single key is provided for applying current impulses of a positive and negative plurality to the condenser 12.

The transmission of a positive impulse is effected by moving the key 21 to engage its upper contact. A circuit is thus completed including the condenser 12, which is thereupon charged positively due to the connection of the positive terminal of the battery with the condenser 12. The grid electrode 11 of the tube 7 is thereby charged more positive with respect to the heated filament 8 as in the previous case. Current is thereby caused to flow in a certain direction through the resistance 19 giving a difference of potential between the terminals of such resistance, which causes a current impulse of a positive polarity to flow through the condenser 20 to the cable 18.

The movement of the key 21 to the left connects the negative terminal of the battery to the condenser 12, which is thereupon charged negatively. The charge of

the condenser in this manner and the release of key 21 permits the condenser 12 to discharge into the input circuit of the tube 7. Since the condenser 12 is charged negatively, the grid electrode 11 will thereupon be charged more negative with respect to the heated filament 8. This causes a current to flow through the resistance 19 in a direction opposite to that previously described 10 when the key 21 was moved to engage the positive terminal of the battery. In this way a current impulse of a negative polarity is transmitted to the line 18 due to the difference of potential existing between the 15 terminals of the resistance 19.

Referring now to Fig. 3, there is shown a symmetrical circuit arrangement comprising two electric discharge devices or vacuum tubes of the audion type, such as 23 and 24. 20 These devices, as in the other cases, are provided with the usual electrodes designated by the numerals 8, 9, and 11. The grid electrodes 11 of these tubes are connected with the battery 25 through the high resistance units 26 and 27 respectively. The cable 18 is connected through a sending condenser 20 to the output circuit of the tubes 23 and 24. In order that the cable 18, when no 25 signals are being transmitted, will be of a potential equal to that of ground, a pair of resistance units 34 and 35 are connected intermediate the cable 18 and ground. Associated with these resistances is a battery 36, and since the resistance of these two 30 resistances is the same, and equal currents flow from the battery 36 through the resistances 34 and 35, the potential of the cable is thereby maintained at the same potential as that of ground. When there 35 are no signals being transmitted, the line is grounded through the resistances 34 and 35 so that any accumulated charge on the cable can be drained off to ground. The input circuit of the devices 23 and 24 is 40 connected with the even-numbered segments of a segmented ring of a rotary distributor 28, which, for the sake of clearness, has been shown developed. All odd-numbered segments of this segmented ring are connected 45 together and the entire group connected to the line terminal of a suitable tape transmitter, such as the well-known Wheatstone type adapted for cable operation. Inasmuch as transmitters of this type are well 50 known to those skilled in the art, and especially since it does not form a part of the present invention, a description thereof is considered unnecessary. The solid ring 29 of the distributor 28 is connected with 55 the condenser 12, which in turn is adapted to be successively connected with the contacts controlled by the tape transmitter and the input circuit of the vacuum tubes 23 and 24, due to the passage of brush 30 over 60 the various segments.

The tape transmitter is adjusted with respect to the distributor, whereby the contacts controlled thereby for connecting the battery 32 with the odd-numbered segments of the distributor ring closes just prior to 70 the passage of the brush 30 over these segments and opens just after the brush has passed from one of these segments. If in the transmission of a message the negative terminal of the battery 32 is connected with the odd-numbered segments of the distributor, due to the passage of a hole in a perforated tape of the tape transmitter (not shown), which causes the closure of contact 31, condenser 12 will be charged in 75 accordance therewith upon the passage of brush 30 over the odd-numbered segment of the distributor ring. The circuit including the condenser 12 may be traced from the negative terminal of the battery 32, contact 31, an odd-numbered segment of the segmented ring of the distributor brush 30, condenser 12, and contact 33 to the other terminal of the battery 32. When the brush 30 passes over an 80 even-numbered segment, the condenser 12 is thereupon connected in circuit with the input of the vacuum tubes 23 and 24. The grid electrode 11 of the vacuum tube 23 is thus made more negative and the grid electrode 11 of tube 24 is made more positive with 85 respect to their respective heated filaments. This thereby causes a decrease in the current flowing through resistances 34 and an increase through resistance 35 and in a direction indicated by the solid arrows. A difference of potential thus exists between the terminals of resistances 34 and 35, which makes the cable terminal negative with 90 respect to ground and causes a current impulse of a negative polarity to flow to the line 18 through the sending condenser 20. This difference of potential will be maintained between the terminals of the resistances 34 and 35 during the passage of the brush over the even numbered segments even though contact 31 has been opened. However, when contact 37 is closed, the condenser 12 will be short-circuited upon the 95 passage of the brush 30 over an odd-numbered segment, thus causing it to be instantly discharged.

In the transmission of a positive impulse over the cable 18, contact 38 is thereby closed due to the operation of the tape transmitter. This connects the positive terminal of the battery 32 with the condenser 12, and upon the passage of the brush 30 over an odd-numbered segment, the condenser will 100 be charged positively. As before, when the brush 30 passes over an even-numbered segment, the condenser 12 will slowly discharge into the input circuit of the tubes 23 and 24. The grid electrode 11 of tube 24 is made 105 more negative while the grid electrode 11 110

115

120

125

130

of tube 23 is made more positive with respect to the respective heated filaments. Thus a current is caused to flow through the resistances 35 and 34 in the direction of the dotted arrows, in which case the potential difference between the terminals of these resistances is increased and the terminal of the cable 18 is made positive with respect to ground. A current impulse of 10 a positive polarity is thereby transmitted over the cable 18. It is thus seen that the arrangement of Fig. 3 is well adapted to send symmetrical positive and negative impulses at a high rate of speed over a cable 15 or line, due primarily to the fact that the use of relay contacts has been entirely avoided.

What is claimed is:

1. A holding relay comprising a space discharge device having a cathode, an anode, impedance control means, and an output circuit, a source of space current in said output circuit, circuit making and breaking means for intermittently impressing potential impulses on said cathode and impedance control means, and means including a condenser, associated with said cathode and impedance control means for prolonging in said output circuit the effect of each of said impressed potential impulses.
2. A holding relay comprising a space discharge device having a cathode, an anode, impedance control means, and an output circuit, a source of space current in said output circuit, circuit making and breaking means for intermittently impressing potential impulses on said cathode and impedance control means, means including energy storing means, bridged across said cathode and impedance control means, for prolonging in said output circuit the effect of each of said impressed potential impulses.

3. Terminal signaling apparatus for a cable or line having large distributed electrostatic capacity, said apparatus comprising means for impressing upon said cable or line at any instant potential of one only of at least two operating values whereby signaling impulses of either polarity and in any desired sequence may be transmitted, said means comprising the combination with a source of direct signaling potential, of high impedance space discharge means in circuit with said source, control means for said space discharge means, and means including a second source of positive and negative potential, electric storage means and circuit making and breaking means for impressing upon said control means potential of any desired one of at least two operating values.
4. Terminal signaling apparatus for a cable or line having large distributed electrostatic capacity, said apparatus comprising means for impressing upon said cable or line at any instant potential of one of at

least two operating values whereby signaling impulses of either polarity and in any desired sequence may be transmitted, said means comprising the combination with a source of direct signaling potential, of high impedance space discharge means in circuit with said source, control means for said space discharge means, and means including a condenser and circuit making and breaking means for impressing upon said control means potential of any desired one of at least two operating values, said condenser being between said circuit making and breaking means and said space discharge means and imparting stored energy to said control means during a portion at least of intervals when said circuit making and breaking means is in open circuit position.

5. In a high speed submarine cable system, the combination with a cable, of means for transmitting signals at such high speed that the chatter produced by the tongue of the pole changing relay ordinarily employed for cable transmission would introduce a high frequency disturbance of a prohibitive value, comprising a space discharge relay at the transmitter in place of said ordinary pole changing relay, said space discharge relay comprising an anode, a cathode and a control element, a source of signaling potential controlled by said space discharge relay, means for associating said source with said cable having negligible reactance at signaling frequencies, a signaling key associated with said control element, and means including a condenser for prolonging after the opening of said key the effect produced by the closure of said key.

6. The combination with a cable or line having large distributed electrostatic capacity, of a source of signaling direct potential, space discharge means in circuit with said source, means for controlling the impedance of said space discharge means, means for impressing either positive or negative signaling impulses upon said control means comprising a source of energy, a signaling key, a condenser adapted to be connected effectively in circuit with either said source of energy through said key or with said control means, and a distributor for effecting said connections alternately.

7. The combination with an electric discharge device having an anode, a cathode and control means, of an output circuit for said discharge device including a source of potential, a condenser, means for impressing a signaling current impulse upon said condenser, and means for subsequently connecting said condenser in circuit with said control means to cause a current variation in said output circuit corresponding to the said signaling current impulse impressed upon said condenser.

8. The combination with an electrical

discharge device having an anode, a cathode and control means, of an output circuit for said discharge device including a source of potential, a condenser, a distributor having conductive segments for impressing signaling current impulses upon said condenser, and for connecting said condenser in circuit with said control means to cause current variations in said output circuit corresponding to the said signaling current impulses impressed upon said condenser.

9. The combination with an electrical discharge device having an anode, a cathode, and control means, of an output circuit for said discharge device including a source of potential, a condenser, means for impressing a signaling current impulse on said condenser, means for subsequently disconnecting said condenser from said signal impressing means, and means for later connecting said condenser in circuit with said control means to cause a current variation in said output circuit corresponding to the said signaling current impulse impressed on said condenser.

10. The combination with an electrical discharge device having an anode, a cathode, and a control means, of an output circuit for said discharge device including a source of potential, a condenser, means including a distributor having conductive segments for impressing signaling current impulses upon said condenser, subsequently disconnecting said condenser from said signal impressing means and later connecting said condenser in circuit with said control means to cause a current variation in said output circuit corresponding to each of the said signaling current impulses impressed on said condenser.

11. The combination with an electrical discharge device having an anode, a cathode and control means, of an output circuit for said discharge device including a source of potential, a condenser, means for impressing signal current impulses upon said condenser, subsequently disconnecting said condenser from said signal impressing means and later connecting said condenser in circuit with said control means to cause a current variation in said output circuit corresponding to each of said signal current impulses impressed on said condenser, said signal impressing means including a distributor having a continuous ring, two sets

of conductive segments, and a brush for electrically connecting said conducting ring with said segments in succession, connections to the segments of one set alternating with the connections to the segments of the other set.

12. The combination with a cable or line for transmitting direct current signals, of a source of signaling potential, two high-impedance space discharge means in opposed relation in circuit with said source, control means for each of said space discharge means, and means including electric storage means for simultaneously impressing positive signaling potential upon one of said control means and negative potential upon the other.

13. The combination with a cable or line for transmitting direct current signals, of a source of signaling potential, two high-impedance space discharge means in opposed relation with said source, control means for each of said space discharge means, and means including a second source of potential, a condenser, and a distributor and a transmitting key for simultaneously impressing positive signaling potential upon one of said control means and negative upon the other, said distributor being effective to connect said condenser in circuit alternately with said second source of potential and said control means of said discharge devices.

14. The combination with a cable or line for transmitting direct current signals, of a source of signaling potential, two substantially equal impedances in series relation in said line and in parallel relation with respect to said source whereby no potential is impressed upon said line or cable from said source when the current through said impedances are equal, a pair of electric discharge devices in circuit with said source and in series with said impedances respectively, control means for each of said discharge devices, means for simultaneously impressing positive potential upon one of said control means and negative potential upon the other of said control means comprising a second source of potential, a key, and means for storing energy from said last mentioned source and later applying it to said control means.

In witness whereof, I hereunto subscribe my name this 16th day of June A. D., 1920.

ALLISON A. CLOKEY.
